UNITED STATES PATENT OFFICE.

CHARLES EDWARD HAVILAND, OF LIMOGES, FRANCE.

DESIGN FOR A DISH.

SPECIFICATION forming part of Design No. 24,634, dated August 27, 1895.

Application filed July 26, 1895. Serial No. 557,247. Term of patent 7 years.

To all whom it may concern:

Be it known that I, CHARLES EDWARD HAVILAND, a citizen of the United States, residing at the city of Limoges, in the Republic of France, have invented and produced a new and original Design for a Dish, of which the following is a specification, reference being had to the accompanying drawings, forming part thereof, and in which—

10 Figure 1 is a top view, partly in section, of a dish bearing my design. Fig. 2 is a side elevation of same and indicates by the dotted line 1 1 the section on which Fig. 1 is taken. Fig. 3 is a detached sectional view through a 15 portion of same on the dotted line 3 3 of Fig. 1.

The leading features of my design consist in the new and original shape and outline of the body of the dish, as shown in the drawings, forming a part of this application.

In the drawings, A designates the body of

the dish, which has a beaded upper edge divided into the large scallops B, the latter being subdivided into the smaller scallops C. The sides of the body A are composed of the 25 scalloped sections D, which correspond with each other and are of the ornate outline illustrated. The lower portion of the sides of the body A curve downward and inward to the base E, which harmonizes with the upper edge 30 of the dish, as more clearly illustrated in Fig. 2.

What I claim is—

The design for a dish, substantially as shown and described.

Signed at the city of Limoges, in the Republic of France, this 8th day of July, A. D. 1895.

CHARLES EDWARD HAVILAND.
